EMIL A. HIRNER, OF ALLENTEWON, PENNSYLVANIA

SAFETY FEED FOR WRINGERS

Application filed March 22, 1929. Serial No. 349,113.

This invention relates to safety devices for feeding material to the squeeze rolls of wash wringers and the like.

The main objects of my invention are to preclude the possibility of the hands being caught between and drawn into the squeeze rolls of wringers; and to attain this end through provision of a simple, inexpensive and easily operated device for the purpose, capable of ready application to all standard types of wringers.

Other objects and attendant advantages of this invention will appear from the detailed description following when taken in connection with the attached drawings, whereof Fig. I is a perspective view of a conventional type of wringer equipped with my improved safety feed, the latter being shown in retracted or loading position.

Fig. II is a cross sectional elevation of the wringer with the parts of the safety feed positioned to correspond with Fig. I.

Fig. III is a perspective view, similar to Fig. I, showing the safety feed in the advanced or feeding position; and,

Fig. IV is a cross section like Fig. II, but with the parts of the safety feed positioned as in Fig. III.

From these illustrations it will be seen that the safety feed of my invention comprises a feed member 10, the same being movable, as hereinafter noted, from the retracted or loading position of Figs. I and II, to the advanced or feeding position of Figs. III and IV in presenting the material M, which is to be wrung, at the bight of the companion squeeze rolls R, R' of the wringer, comprehensively indicated by the letter W. As shown, the feed member 10 embodies a horizontal bar 11 which is angular in cross section, and, beneath the forward edge of said bar is a freely revolving auxiliary progressing roller 12. At 13, the bar 11 has pivotal connection with the upper ends of supporting arms 14 which are fulcrumed at the bottom to brackets 15, secured to the verticals of the wringer frame F at one side by screws 16. The feed member 10 is moreover formed with upwardly reaching extremities 17 which extend forward somewhat at the top as at 17a

and carry lateral projections 18 arranged to engage vertical slots 19 in ears 20 of the brackets 15. Rearward of the projections 18, the extremities 17 of the feed member 10 afford pivotal connection for a hanger 21 with drooping side arms 22 integrally joined by a transverse rod 23 whereof the ends normally rest on the forward extensions 17a of said extremities. Suspended from the hanger 21 is a finger guard 25 constituting a shield across the front of the squeeze rolls R, R' of the wringer W. The outward swing of the feed member 10 is limited, as shown in Figs. I and II, through contact of the projections 18 on the extremities 17 with the bottoms of the slots 19 in the brackets 15; while the inward swing is limited through engagement of stops 14a on the arms 14 with the wringer frame as shown in Fig. IV.

The operation of the device is as follows: With the feed member 10 retracted as in Figs. I and II the leading end of the material M is laid on the bar 11 so as to overlap the auxiliary progressing roller 12. The feed member 10 is then moved inward by hand to the position of Figs. III and IV with the result that the lapping end of the material M is pressed, by the auxiliary progressing roller 12 against the lower squeeze roll R' of the wringer W. Through motion thereby induced in the roller 12 the fold of the material M is advanced so as to be caught in the bight between the roll R' and its companion R. In this connection it is to be particularly noted that the feed member 10 is maintained under the influence of gravity both in the retracted or loading position and the advanced or feeding position by virtue of the swing of the supporting arms 14 to opposite sides of the vertical or dead center. It is moreover to be noted that through proportioning of the various interconnections involved, the finger guard 25 is ordinarily lifted just sufficiently to clear the material M as it is presented to the squeeze rolls R, R' incident to the inward swing of the feed member 10.

When necessary, access may be had to the squeeze rolls R, R' of the wringer W from the front by lifting the hanger 21, as shown in dot-and-dash lines in Fig. II, thereby to

raise the finger guard 25, the movement being checked through contact of side projections 26 of said guard with stop lugs 27 at the tops of the brackets 15. Then again, the finger guard 25 may be entirely cleared in the elevated position by shifting it inwards (toward the wringer frame) so that the projections 26 are displaced through slots 28 between the lugs 27 and parallel lugs 29 beneath, said slots being open at the back as indicated at 30. With the projections 26 thus freed, the guard 25 can be swung over the top of its pivots, and the suspension hanger 21 in turn swung rearward in a manner entirely obvious from Fig. II.

The wringer W chosen for the purpose of illustration herein is of a reversible type common in connection with modern washing machines, it being mounted to swing horizontally about a column C and provided with a drain chute S which is oppositely tiltable as shown in dot-and-dash lines in Fig. II. To enable use of the safety feed 10 in the reverse position of the wringer W if desired, the other side of the wringer frame may be drilled and tapped to take the bracket screws 16 incident to transposal of the feed device to that side of said frame.

Having thus described my invention, I claim:

1. A safety feed for wringers having squeeze rolls comprising a horizontally-pivoted gravity-influenced feed member with an associated freely-rotatable roller for presenting material to be wrung at the bight of the squeeze rolls, a finger guard for shielding the rolls, and means operatively co-ordinating said guard with the feed member for induced movement to clear the material concurrent with its presentation to the wringer squeeze rolls.

2. A safety feed for wringers having squeeze rolls comprising a horizontally-pivoted gravity-influenced angle-section feed member with a freely-rotatable roller at the forward edge for presenting material to be wrung at the bight of the squeeze rolls, a depending finger guard shielding the rolls, and pivotal means operatively co-ordinating said guard with the feed member so that the former is lifted clear of the material concurrent with its presentation to the squeeze rolls.

3. A safety feed for wringers having squeeze rolls comprising a horizontally-pivoted angle-section feed member with an associated freely-rotatable roller, a mounting including connections operatively co-ordinated to said feed member whereby the latter is swingable from retracted or loading position to advanced or active position in presenting material at the bight of the squeeze rolls, and means restraining the feed member against the influence of gravity in either position.

4. A safety feed for wringers having squeeze rolls comprising a horizontally-pivoted

angle-section feed member with a freely-rotatable roller at the forward edge, a mounting including arms fulcrumed at their lower ends to the wringer frame with their upper ends pivotally supporting the feed member whereby the latter is swingable from retracted position at one side of the dead center of said arms, to advanced position at the other side in presenting material at the bight of the wringer squeeze rolls, and means restraining the feed member against the influence of gravity in either position.

5. A safety feed for wringers having squeeze rolls comprising a horizontally-pivoted angle-section feed member with a freely-rotatable roller at the forward edge, a mounting including arms fulcrumed at their lower ends to the wringer frame with their upper ends pivotally supporting the feed member, whereby the latter is swingable from loading position at one side of the vertical center of the arms to active position at the other side in presenting material at the bight of the wringer squeeze rolls, and stops to limit movement of the feed member in opposite directions.

6. A safety feed for wringers having squeeze rolls comprising a horizontal feed member having upwardly directed extremities with lateral projections, a mounting including arms fulcrumed at their lower ends to the wringer frame with their upper ends pivotally supporting the feed member whereby the latter is swingable from retracted position at one side of the vertical dead center of the arms to advanced position at the other side in presenting material to the wringer squeeze rolls, and fixed brackets with vertical guide slots for engagement by the lateral projections of the upwardly directed extremities of and also limiting outward movement of the feed member aforesaid.

7. A safety feed for wringers having squeeze rolls comprising a horizontal feed member embodying upwardly directed extremities having lateral projections, a mounting including arms fulcrumed at their lower ends on the wringer frame with their upper ends pivotally supporting the feed member whereby the latter is swingable from retracted position at one side of the vertical dead center of the arms to advanced position at the other side in presenting material to the wringer squeeze rolls, fixed brackets with vertical guide slots for engagement by the lateral projections of the upwardly directed extremities of the feed member, said projections serving as stops in contacting with the bottoms of the slots to limit the outward swing of the feed member, and a stop on the feed member, for contact with the wringer frame, to limit its inward swing.

8. A safety feed for wringers having squeeze rolls comprising a horizontal feed member for presenting material at the bight

of said squeeze rolls, said member having upwardly reaching extremities, a finger guard to shield the squeeze rolls, and a hanger mounting pivotally co-ordinating the feed member extremities with the finger guard so that the lower edge of said latter guard is lifted clear of the material incidental to presentation as aforesaid.

9. A safety feed for wringers having squeeze rolls comprising a horizontal feed member for presenting material at the bight of the squeeze rolls, said member having upwardly reaching extremities, a finger guard pivotally hung from said extremities in front of and to shield the squeeze rolls, a mounting for the feed member including arms fulcrumed at their lower ends on the wringer frame and pivotally supporting the feed member, and a pivotally mounted hanger co-ordinating the feed member and finger guard thereby so as the former is swung upward from a retracted position to advanced position lifting of the bottom edge of the finger guard clear of the material takes place incidental to presentation of the material at the bight of the squeeze rolls aforesaid.

10. A safety feed for wringers having squeeze rolls comprising a horizontal feed member for presenting material at the bight of the squeeze rolls, said member having upwardly reaching extremities, a pendant finger guard in front of and to shield the squeeze rolls, a supporting hanger for the finger guard with rearward arms having pivotal connection on the extremities of the feed member to enable lifting of said guard for access to the feed rolls when required, and a mounting with vertical guide slots defining movement of the feed member so that the lower edge of the finger guard is normally lifted sufficiently to clear the material incidental to presentation at the bight of the squeeze rolls aforesaid.

11. A safety feed for wringers having squeeze rolls comprising a horizontal feed member for presenting material at the bight of the squeeze rolls, an auxiliary roller on the feed member adapted to contact with one of the squeeze rolls, a finger guard for shielding the rolls, and a pivotal hanger operatively co-ordinating the feed member and finger guard to elevate the latter to clear the material incidental to its presentation at the bight of the squeeze rolls aforesaid.

55. In testimony whereof, I have hereunto signed my name at Allentown, Penna., this 19th day of March, 1929.

EMIL A. HIRNER.
